4 Claims. (Cl. 128—271)

ABSTRACT OF THE DISCLOSURE

This invention concerns a suppository containing at least two active ingredients in which one or more active ingredients are confined to one portion of the suppository, while one or more other active ingredients are confined to another portion of the suppository, and methods of making said suppository containing the active ingredients.

This invention relates to suppositories and in particular provides a suppository with which one is able to administer, in the same formulation, ingredients which are mutually incompatible.

According to the present invention there is provided a suppository containing at least two active ingredients and in which one or more active ingredients are confined to one portion of the suppository, while one or more other active ingredients are confined to another portion or portions of the suppository.

There are frequently instances where it would be desirable to administer, simultaneously by means of a suppository, active substances which are mutually incompatible and this can now be done using the suppository of the present invention. Examples of groups of substances which it may be desired to formulate together in a suppository but which are mutually incompatible are the following:

Cocaine	}	incompatible with	lethethylmethyl
Codine	}	}	tannines.
Morphine	}	}	iodides.
Chloral hydrate	}	incompatible with	alkali metal carbonates.
	}	}	barbiturates.
Aminophyllin and	}	}	tannic acid.
local anaesthetics	}	}	iodides.
of procaine type.	}	}	
Adrenaline	}	incompatible with	
Atropine	}	}	tannic acid.
Cetrimide	}	}	
Benzalkonium chloride	}	incompatible with	diethylsodium sulphosuccinate.

Suppositories normally have an elongated shape and the active ingredients may be confined to different portions extending longitudinally of the suppository although it is preferred that the suppository is divided transversely into portions abutting end to end and containing the separated ingredients.

Where the suppository is divided transversely, it is advantageously employed as a means for administering different active ingredients to different parts of the tract to be treated. For example, in the treatment of internal haemorrhoids it is customary to administer a vasoconstrictor decongestant by means of a suppository to the rectal mucosa, i.e. above the ano-rectal sphincter, since the drug is absorbed through the rectal mucosa, although the pain resulting from haemorrhoids is due to inflammation of and tension in the anal canal and consequently relief of this pain will be effected by the application of local anaesthetic to the anal canal, i.e. below the ano-rectal sphincter. In order to achieve the greatest effect from the decongestant and the local anaesthetic, therefore, the decongestant should be concentrated at the rectal

2

tal mucosa while the anaesthetic is concentrated at the site of the inflammation in the anal canal and this disposition of the active substances may be readily attained when they are formulated in a suppository in accordance with the invention in which the vasoconstrictor decongestant is confined to a portion of the suppository which is inserted first into the rectal passage and the local anaesthetic confined to the remaining portion of the suppository.

10 By confining the decongestant or other suitable drug to that portion of the suppository which penetrates above the ano-rectal sphincter, it is possible to administer the drug in more accurate doses since the whole of the drug is released at the site of the rectal mucosa from which it is absorbed and loss of the drug arising from release into the anal canal, as occurs in the case with conventional suppositories, is minimised.

Suppositories in accordance with the invention may be prepared by mixing separately the active substances 20 which it is desired should be confined to different portions of the suppository with a conventional suppository base, such as a petroleum jelly, cocoa-butter or a triglyceride, preferably in the presence of a dispersing agent, moulding the separate mixtures into the desired complementary shaped portions and pressing the ends of the shaped portions together, or melting the ends and touching them together, so that they adhere to form the final suppository. Other conventional ingredients may be incorporated into one or more portions of the suppository, 30 such as antiseptics, analgesics and astringents.

In order to identify the particular formulation of the suppository and also to indicate which end of the suppository should be inserted first into the tract to be treated, it is possible to incorporate different colouring 35 materials into the portions of the suppository which contain different active substances.

The following example is given to illustrate the invention and the manner in which it may be carried into effect:

40 The following ingredients were mixed together and the resulting mixture shaped to form the upper or leading portion of a suppository for treating haemorrhoids:

	MG.
Phenylephrine hydrochloride (decongestant)	7.5
Oil soluble colour, q.s.	
Triglyceride base to	900

The complementary portion of the suppository was formed by mixing the following ingredients and shaping the resultant mixture:

	MG.
Amethocaine hydrochloride (local anaesthetic)	10
Bismuth subcarbonate (astringent)	100
Tyloxytol (dispersing agent)	25
Oil-soluble colour, q.s.	
Triglyceride base to	1900

60 The ends of the two portions were joined by pressing them together or by melting the ends and touching them together and a final suppository was obtained which weighed 2.8 grams. The colouring materials employed in the two portions were different so that the active ingredient in each portion could be identified.

It will be appreciated that the invention is not limited by the specific Example above set forth and that various modifications are possible; for example, instead of separately shaping the two portions of the suppository and joining them as described, the molten complementary composition may be cast into a mould containing the solidified first portion thus automatically securing a bond 70 between the two portions.

It will also be appreciated that the invention is not

limited to formulations in which there are mutually incompatible ingredients which have to be kept separate from one another since it is an entirely separate advantage of this invention that different ingredients may be suitably positioned in use to exert their particular effects to the greatest advantage whether those ingredients are compatible or incompatible.

The accompanying drawings are diagrammatic illustrations of the two essential forms of suppositories in accordance with the present invention.

We claim:

1. A suppository containing at least two active ingredients and divided transversely into two portions abutting end to end, one or more of the active ingredients being confined to one portion and one or more of the other active ingredients being confined to the other portion, one of the active ingredients being a decongestant agent and another being a local anaesthetic agent, the decongestant agent being in the end portion of the suppository intended for insertion into the patient.

2. A method of manufacturing a suppository as in claim 1 which comprises separately mixing with a sup-

pository base the active ingredients which are to be separated from one another, moulding the first mixture in a mould to form a first complementary portion, casting the second molten mixture into the mould containing the solidified first portion in order to mould the second portion into contact with the first portion.

3. A suppository according to claim 1 wherein the separated ingredients are incompatible with one another.

4. A suppository according to claim 1 wherein colouring material is incorporated into one or more of the portions.
